Primary Examiner—Susan J. Lucas**Attorney, Agent, or Firm—Terry M. Gernstein****[57]****CLAIM**

The ornamental design for a flashing signal for home emergency alarm system, as shown and described.

DESCRIPTION

FIG. 1 is a front perspective view of a flashing signal for home emergency alarm system showing my new design;

FIG. 2 is a front elevational view thereof;

FIG. 3 is a side elevational view thereof, the side opposite being a mirror image of the side shown in FIG. 3;
FIG. 4 is a top plan view thereof; and,
FIG. 5 is a bottom view thereof.

FIG.1.

FIG. 3.

FIG. 2.

FIG. 5.

FIG. 4.
